UNITED STATES PATENT OFFICE.

GEORGE M. ARMSTRONG, OF BALTIMORE, MARYLAND.

DEVICE FOR APPLYING GRIPS.

Application filed April 11, 1922. Serial No. 551,749.

To all whom it may concern:

Be it known that I, GEORGE M. ARMSTRONG, citizen of the United States, residing at Baltimore, in the county of Baltimore City and 5 State of Maryland, have invented certain new and useful Improvements in Devices for Applying Grips, of which the following is a specification.

This invention relates to a novel device for 10 applying tubular grips to the handles of golf clubs or the like.

Heretofore considerable difficulty has been experienced in properly applying and setting tubular sheaths or grips to the handles 15 of playing clubs such as golf sticks, and the present invention has primarily in view a novel device for overcoming this difficulty, thereby permitting elastic or equivalent tubular grips to be applied with facility and accuracy. In that connection the invention 20 contemplates a simple and practical device in the nature of a form or carrier that may readily receive the tubular member and expand it to sufficient diameter to enable it to be readily placed upon the stick without difficulty, and thereafter be taken apart to permit the sheath to rest upon the handle of the shaft precisely in the desired position.

A further object of the invention is to provide 25 a device that may be economically manufactured; simple to operate; readily taken apart and assembled; and which is also substantial and durable thereby providing a device capable of giving maximum service.

With the above and other objects in view 30 which will more readily appear as the nature of the invention is better understood, the same consists in the novel construction, combination and arrangement of parts hereinafter more fully described, illustrated and claimed.

A preferred and practical embodiment of the invention is shown in the accompanying drawings in which:—

Figure 1 is an elevation of the improved device.

Figure 2 is an elevation of the device illustrating the initial step in its use.

Figure 3 is a view similar to Figure 2 50 showing the device telescoped over the end of the golf stick for the purpose of positioning the grip thereon.

Figure 4 is a view similar to Figures 2 and 55 3 showing how the device is taken apart in order to permit the tubular grip to be left on the handle of the stick.

Figure 5 is a cross sectional view taken on the line 5—5 of Figure 3.

Figure 6 is a cross sectional view taken on the line 6—6 of Figure 3. 60

Figure 7 is a detail longitudinal sectional view taken on the line 7—7 of Figure 3.

Figure 8 is an enlarged detail front elevation of the expander plug.

Figure 9 is a cross sectional view taken on the line 9—9 of Figure 7. 65

Similar reference characters designate corresponding parts throughout the several figures of the drawings.

In carrying the present invention into effect it is proposed to provide a collapsible mandrel or form of skeleton formation to readily receive a tubular elastic golf grip G in such a manner that it may be readily expanded to be fitted or placed over the 70 handle portion of the golf stick thereby to enable the same to be shifted circumferentially of the shaft to be placed accurately in the desired position. In that connection the invention is of special utility in applying 75 golf grips of the type set forth in my pending application Serial No. 530907 filed January 21, 1922, which have a sight-line or marker which bears a definite relation to the head of the club or stick and therefore must 80 be accurately set on the shaft in order to enable the same to properly function as a sighting-marker. 85

The advantages of elastic or yieldable grips for the handles of golf clubs or the 90 like are readily appreciated and understood by those familiar with the handling of the clubs, but heretofore it has been practically an impossibility to successfully apply rubber or similar grips of tubular form because, in 95 order to provide a successfully attached grip, the same must be applied in such a manner as to be under tension. If the grip is initially made of a diameter to readily slip or slide onto the handle of the stick, it is difficult to 100 attach the same in a manner that it will not slip or turn when the club is used. On the other hand it is difficult to provide a grip of smaller diameter initially than the shaft, and having sufficient body as well as anti-slipping 105 qualities, which can be readily placed on the shaft by rolling or the like.

Accordingly, the present invention has in view the provision of a device which will fit into the tubular grip and readily expand 110 the same so that it may be fitted over the handle in a manner to permit of its being

readily shifted or adjusted prior to the removal of the several parts to effect its release thereby making it possible to quickly and accurately position the grip in the desired manner on the shaft, and subsequently remove the device.

In its general aspect the present device includes a skeleton collapsible form or mandrel A comprising a plurality of expander 10 fingers 1 which may be held in their spaced and assembled relation by a suitable base piece B, and shifted diametrically in the expanding operation by means of an expander plug C that is preferably in the form 15 of a cone to facilitate its movement between the expander arms.

Obviously, the above general organization of parts may assume various forms of embodiment, but a preferred and practical arrangement and construction thereof is shown 20 in the accompanying drawings from which it will be observed that the expander fingers 1 are preferably relatively long narrow strips of metal held in spaced and assembled 25 relation by fitting into the spaced sockets 2 of the base piece B. As will be observed from Figure 9 these sockets are preferably equi-distantly spaced in the side wall of the central boss portion 3 of the base and for the 30 purpose of retaining and holding the ends of the expander fingers in the sockets a suitable retaining ring 4 may be employed. This ring is preferably provided at its inner face with a plurality of offset portions 35 5 for registering with the sockets 2 to clamp the fingers in the sockets, but when rotated so that the offset portions or abutments 5 are out of registry with the sockets the fingers may be released. 40 For convenience in maintaining the ends of the fingers opposite the base piece in closed relation when the device is stored or not in use a suitable thimble or cap 6 may be employed. This cap also serves to keep 45 the ends of the expander fingers in position while the grip is being pushed over the same.

In connection with the means for expanding the fingers 1 it will be observed that the expander plug C preferably includes the 50 conical entering portion 7 and the relatively flat skirt or band 8 provided with guiding recesses 9 for receiving and guiding the expander fingers 1 as the plug is pushed therebetween as will presently appear. The base 55 of this plug is provided with a socket portion 10 for fitting over the end of a suitable starting abutment 11 which may be placed upon the edge of a bench or the like as shown in Figure 2, and to also thereafter 60 act as means for receiving the end of the golf stick S in the further manipulation of the device. It will also be observed that the thimble 6 serves to hold the expander arms 1 in position so that each arm will be assembled to fit in the proper notch 9 of the cone

C while their opposite ends fit correctly in the notches 2 of the base. In other words it is necessary to maintain the arms parallel by keeping the same in notches 9 and 2 respectively of the cone and base which are in 70 registry.

The manner in which the device is used is substantially as follows:—

Assuming that the device is in the condition shown in Fig. 1 the cap 6 may be removed and the expander plug C taken out. The cap 6 may be then replaced over the ends of the arms 1 to facilitate the placing of the grip G thereon. That is to say, the cap or thimble 6 may be replaced over the 80 ends of the arms after the cone C has been taken out so as to maintain the arms in proper relation and thereby enable the cone to be readily positioned so that the arms will properly fit into the proper notches thereof. 85 The expander plug C may then be placed over and against the button or abutment 11 on a bench or other support and the ends of the fingers 1 pressed over the cone 7 and into the guiding notches 9 of the plug to 90 effect the initial expansion of the fingers 1. Owing to the relative elasticity of the grip G the fingers 1 will be securely held within the notches and the entire device shown in Figure 2 may be removed from the abutment 11 and the socket 10 of the expander plug C fitted over the end of the golf stick S. The golf stick is then held relatively stationary and the present device is pushed over the end of the stick until the cone C travels and 95 entirely clears the end of the tubular grip. While the parts are in this position as shown in Figure 3 it will be apparent that the grip may be readily adjusted circumferentially of the handle of the golf stick S and when the 100 desired set is obtained the device may be dismembered and removed.

To effect the removal the method outlined in Figure 4 may be followed. That is to say the ring 4 which retains the ends 110 of the fingers in the sockets 2 may be rotated so as to shift the abutments 5 out of registry with the sockets to release the fingers whereupon the base piece may be readily detached and the expander plug C 115 is also removed. The expander fingers 1 may then be individually removed from between the grip and the shaft thereby permitting the grip to contract onto and snugly fit the shaft without disturbing the position 120 in which it has been set by the manipulation of the collapsible mandrel or frame.

For a great many years manufacturers of golf grips as well as players have recognized the desirable qualities of the rubber 125 grip but their plans to utilize rubber have been frustrated by their inability to provide a method of securely fastening the grip on the stick. Rubber cement, glue, paste, and other materials have been employed in the 130

effort to securely fasten the grip either to the wooden stick itself or to various fabrics themselves fastened securely to the wood, but no method had been found which would 5 prevent the rubber grip, sooner or later, turning on the shaft. By wrapping the club first with friction tape and employing this method to put the grip in place, this difficulty is overcome, as the grip remains 10 firmly adhered to the tape in the position in which it was applied.

Without further description it is thought that the features and advantages of the improvement will be readily apparent, and it 15 will of course be understood that changes in the form, proportion and minor details of construction may be resorted to, without departing from the spirit of the invention or scope of the appended claims.

20 I claim:—

1. A device for applying grips to the handles of playing clubs comprising an expandable and contractible form adapted to receive thereon the tubular elastic member constituting the grip, an expanding device 25 adapted to be engaged by the club handle and moved thereby and therewith through the form causing the latter to expand, and releasable means temporarily holding the 30 form intact during the expanding operation.

2. A device for applying grips to the handles of playing clubs comprising an expandable and contractible form adapted to receive thereon the tubular elastic member 35 constituting the grip, means for expanding said form by the act of inserting the club handle therein, whereby the grip will be stretched over the handle, and releasing means for the form permitting the grip to 40 contract on the handle and also permitting the independent removal of the form from between the handle and the grip.

3. A device for applying grips to the handles of playing clubs comprising a plurality 45 of fingers adapted to receive thereover the tubular elastic member constituting the grip, temporary holding means releasably engag-

ing one end of said fingers, and an expanding element adapted to be engaged by the club handle and moved thereby and therewith inside of the fingers causing the latter with the grip thereon to expand, said expanding device being adapted to pass out of the form at the end where the fingers are held by said holding means.

4. A device for applying tubular grips to the handles of playing clubs including a collapsible mandrel consisting of a plurality of expander fingers, a combined spacing and carrier member for one end of the fingers, means for holding said fingers thereto, and an expander plug adapted to engage with the other end of said fingers and be shifted longitudinally thereof to expand the same diametrically, said expander plug consisting of a conical body having a plurality of notches in the circumference thereof for receiving and guiding the expander fingers and also provided with a socket.

5. A device for applying tubular golf 70 grips to the handles of playing clubs including a skeleton collapsible mandrel comprising a plurality of expander fingers, a base piece having spaced sockets for receiving one end of the fingers, means for detachably holding said fingers in the sockets of the base piece, and an expander plug for cooperating with said fingers.

6. A device for applying tubular golf 80 grips to the handles of playing clubs including a skeleton collapsible mandrel comprising a plurality of expander fingers, a base piece having spaced sockets for receiving one end of the fingers, a retaining ring for detachably holding said fingers in the 85 sockets of the base piece, and an expander plug for cooperating with said fingers.

In testimony whereof I hereunto affix my signature in the presence of two witnesses.

GEORGE M. ARMSTRONG.
